Patented May 17, 1904.

UNITED STATES PATENT OFFICE.

WALTER BRINTON, OF HIBRIDGE, AND WALTER GASTON, OF PLAINFIELD, NEW JERSEY.

DESIGN FOR A SAFE OR VAULT BODY.

SPECIFICATION forming part of Design No. 36,919, dated May 17, 1904.

Application filed October 15, 1903. Serial No. 177,224. Term of patent 14 years.

To all whom it may concern:

Be it known that we, WALTER BRINTON, residing at Highbridge, in the county of Hunterdon, and WALTER GASTON, residing at Plainfield, in the county of Union, State of New Jersey, citizens of the United States, have invented a new, original, and ornamental Design for a Safe or Vault Body, of which the following is a specification, reference being had to the accompanying drawings, forming a part thereof.

Figure 1 is a front view of a safe or vault body, showing the new design. Fig. 2 is a rear view of such body, showing such design; and

Fig. 3 is a side view of such safe or vault body, 15 showing the design.

We claim—

An ornamental design for a safe or vault body, substantially as shown.

WALTER BRINTON.

WALTER GASTON.

Witnesses as to Walter Brinton:

JACOB STRUHLE,
A. F. MURRAY.

Witnesses as to Walter Gaston:

VOLNEY W. MASON, Jr.,
SYDNEY L. SMITH.
